INVENTOR.
RAYMOND E. MOORE.
BY *Thom. Matteson.*

ATTORNEY.

UNITED STATES PATENT OFFICE.

RAYMOND G. MOORE, OF BRIDGEPORT, CONNECTICUT, ASSIGNOR TO THE BASSICK COMPANY, OF BRIDGEPORT, CONNECTICUT, A CORPORATION OF CONNECTICUT.

LOCK HANDLE.

Application filed February 14, 1924. Serial No. 692,634.

This invention relates to an improved lock handle, particularly of the type adapted for use with the locks or latches of automobile doors. As is well known the outer surface 5 of an automobile door is not always in a parallel plane with the lock, being in some cases inclined vertically and in others horizontally, with the result that the mounting of the handle and its escutcheon plate is imperfect, and does not permit of the proper functioning of the handle.

An object of the present invention, therefore, is to provide a handle structure having an escutcheon mounted for universal movement, to the end that the same may be secured to the door in a manner as to permit the handle to be properly positioned at right angles to the lock, and to turn freely, without binding or looseness, irrespective of 20 the angular position of the escutcheon.

Another object is to provide such a handle construction in which the handle may be operated with facility, and in which there will be no end play or rattling. A further 25 object is to provide a bearing between the handle and escutcheon which will at all times be weather tight, so that dust or moisture cannot seep into the interior of the door.

Other objects are to provide a device which is neat in appearance, simple and economical in construction, and free from 30 any parts which might readily get out of order.

With the above and other objects in view, an embodiment of my invention is shown in the accompanying drawings, and this embodiment will be hereinafter more fully described with reference thereto, and the invention will be finally pointed out in the 40 claims.

In the drawings:

Fig. 1 is a perspective view of a handle according to the present embodiment of the 45 invention, and showing the same attached to an automobile door;

Fig. 2 is a plan view of the handle, and showing the door and lock to which it is attached in horizontal section;

Fig. 3 is a vertical sectional view of the 50 handle, taken along the line 3-3 of Fig. 2; and

Fig. 4 is a perspective view showing the 55 several parts of the handle in separated and aligned relation.

Similar reference characters indicate corresponding parts throughout the several figures of the drawings.

Referring to the drawings, the embodiment of the invention shown therein is shown 60 attached to an automobile door 10, having a lock or latch 11 set in the rear side thereof adjacent the rabbeted edge, and provided with an oscillating roll-back 12 constituting the actuating element of the latch, said roll-back having a square cross section bore for the insertion of the square handle shaft. The door is furthermore provided at its front side with a drilled hole 13 in line with the roll-back and adapted to receive the 70 handle shaft.

The handle consists of a cylindrical shank 14 provided at its outer end with a hand plate or grip 15, and at its inner end with a reduced cylindrical extension 16 having a 75 collar 17 secured thereon adjacent the shoulder between the shank and said extension, said collar being provided with an inner spherical surface 18 forming an annular spherical surfaced recess about the extension. The collar 17 may be swaged, brazed, or otherwise suitably secured, or it may, if desired, be formed integral with the handle shank. At the extremity of the extension 16 there is provided a reduced shouldered 80 end portion 19 for receiving a spring retaining washer, as will hereinafter more fully appear.

The handle shaft 20 is of square cross section to fit the bore of the roll-back 12, and is provided with a knurled cylindrical extension 21 which is forced into a socket 22 provided in the handle shank 14, the shoulder 23 between the square and cylindrical portions of the shaft abutting the 95 end of the portion 19 of the extension 16. An annular groove 24 is provided in the extension 21 adjacent the shoulder 23, and into which the metal at the inner extremity of the shank is forced to thereby securely 100 connect the shaft.

The escutcheon plate 25 is of elongated form and is provided near its upper and lower ends with holes 26, which are engaged by screws 27 to attach the plate to the door. A spherical boss 28 is pressed forwardly 105 from the center of the plate and is apertured, as at 29, to engage about the extension 16 of the handle shank in spaced relation thereto, the outer spherical surface of 110

the boss being of corresponding radius to the spherical recess 18 and snugly engaging within the same.

At the inner side of the escutcheon plate, 5 and disposed within the boss 28 and about the extension 16 of the shank, there is provided a collar or shell 30, of substantially hemi-spherical form, and apertured at its forward end, as at 31, to snugly engage 10 about the extension, its inner end extending slightly rearwardly of the inner surface of the escutcheon plate.

A coil spring 32 is disposed about the extension 16 within the shell, and is compressed, 15 to force the shell forwardly, by means of a retaining washer 33 secured by swaging, as at 34, upon the reduced end portion 19 of the extension 16, the escutcheon being thereby centered and yieldably held in 20 position within the spherical recess 18.

The clearance between the parts is just sufficient to permit of the angular adjustment of the escutcheon plate to any desired position to conform to the surface of the door, 25 as shown for instance in Fig. 1, and in dotted lines in Figs. 2 and 3, and at the same time allow of the free rotary action of the handle. As is clear from Fig. 3 the spacing of the aperture 29 of the boss 28 from the extension 16, and the rounded corner between the boss and the flat surface of the escutcheon plate will permit of an appreciable angular 30 rotation of the escutcheon about the shell 30 in any desired direction. The relation of 35 the parts is such that there is no appreciable end play and the handle will always function properly without looseness or rattling. If desired a washer may be interposed between the forward end of the spring 32 and the shell 30 to prevent any possibility of jamming, but in the embodiment illustrated this 40 is not deemed essential.

It is obvious that any wear upon the parts, 45 through excessive use of the handle, is automatically taken up by the action of the spring, so that a tight, non-rattling structure is provided and maintained at all times.

According to the invention the several 50 parts of the structure are assembled by the single operation of securing the handle shaft in the shank, and as clearly shown in Figs. 3 and 4. The escutcheon plate, shell, spring, and retaining washer are engaged in their proper relation upon the extension 16, and 55 thereupon the shaft is forced into the shank by suitable pressure applying means, the expansion of the metal and the swaging of the end 19 inwardly into the groove 24 and outwardly behind the washer through abutment 60 of the shoulder 23 with the end of the shank tightly securing the washer in place, and re-

taining the parts in their assembled relation.

I have illustrated and described a preferred and satisfactory embodiment of the 65 invention, but it is obvious that changes may be made therein, within the spirit and scope thereof, as defined in the appended claims.

Having thus described my invention, what I claim and desire to secure by Letters 70 Patent is:

1. In a lock handle, a rotatable shaft, a spherical apertured concavo-convex bearing for said shaft adapted to be fixed to a door with its aperture in annularly spaced relation to said shaft, a fixed shoulder on said shaft having a spherical annular recess engaging the convex side of said bearing, said shaft including a cylindrical portion extending inwardly from said shoulder, a substantially half-spherical apertured shell member 75 slidably engaged upon and disposed annularly about said cylindrical portion of said shaft and engaging the concave side of said bearing, a washer secured on said shaft and adapted to be abutted by the large end of said shell member, and spring means disposed within said shell member between the inner spherical surface and said washer and yieldably pressing the same into engagement 80 with said bearing to permit universal movement between said shaft and bearing.

2. In a lock handle, a rotatable shaft including a fixed shoulder having a spherical annular surface and a cylindrical portion extending inwardly from said shoulder, said cylindrical portion having a reduced annularly recessed inner end portion, said shaft having a socket extending from said inner end portion forwardly, a shank having a 100 reduced extension adapted to be inserted in said socket, an abutment shoulder being provided at the junction of said shank and extension, a universal bearing for said shaft including spring pressed parts assembled about said cylindrical shaft portion and adapted to bear upon said fixed shoulder, and a retaining washer for said assembled spring pressed parts of the bearing engaged upon said annular recessed end of the cylindrical shaft portion, said recessed end including an outwardly swaged portion fixedly securing said washer and produced by expansion of the metal at the inner end of said shaft through insertion of said shank extension into said socket and abutment of said abutment shoulder against the inner end of said shaft.

Signed at Bridgeport, county of Fairfield, 110 and State of Connecticut, this 12th day of February, 1924.

RAYMOND G. MOORE.
